UNITED STATES PATENT OFFICE.

PATRICK GOODMAN, OF BROOKLYN, NEW YORK.

GAS-MAIN STOPPER.

Application filed October 26, 1926. Serial No. 144,340.

The present invention is an improvement on the gas-main stoppers forming the subject matter of United States Patent Number 940,458, granted to me November 16th, 1909; Patent Number 960,086, granted to me May 31st, 1910; and Patent No. 1,539,730, granted to me May 26th, 1925. In said patents the assemblage comprises a collapsible frame having a diaphragm which is adapted to be passed through an opening in the side of the gas-main and then expanded in the main to cut off the flow of gas, said frame having handle bars to extend through the opening to the exterior and having means arranged to force the handle bars in opposite directions to lock the stopper in place.

The general object of the present invention is to strengthen the structure by providing bracing means between one of the handle bars and the collapsible frame.

Reference is to be had to the accompanying drawings forming a part of this specification, it being understood that the drawings are merely illustrative of one example of the invention.

Figure 1 is a side view of a gas-main stopper embodying my improvements, the stopper being shown locked in position in the main, and the main in longitudinal central vertical section;

Figure 2 is a vertical section substantially on the line 2—2 of Figure 1;

Figure 3 is an inner face view of the stopper when collapsed, showing the handle-bars in section;

Figure 4 is an enlarged view in vertical section of the sleeve applied to one handle bar, the latter shown in side elevation.

The stopper proper in which the present improvements are embodied has a collapsible spring frame 10 covered by a yielding packing and having a flexible diaphragm 11 which is stretched across the frame in circular form by exerting pressure on the frame at diametrically opposite points. At these points the frame is provided with pivotally connected telescoping members 12 and 12^a, bridging the diaphragm, and pivotally connected handle-bars 13 and 14, each bar being provided with suitable hand-grips 15 and 115. A hook designated generally by the numeral 16 is provided, having a threaded shank extending through the hand-grip 115 and provided with a tightening nut 17 and a set nut 18. The hooked end 19 of the hook 16 is adapted to engage beneath a

vertically slotted lug 20 on a sleeve 21 fitted on the handle bar 14, said sleeve having a set screw 22. Depending from the sleeve 21 is a bracket 23 having a foot 24 at the lower end adapted to engage the gas-main at the opening formed therein for the insertion of the stopper.

With the described arrangement, when the sleeve 21 is positioned on the handle-bar 14 with the foot 24 engaging the gas main at the edge of the opening, the hook 19 is engaged beneath the lug 20. It is to be observed that said lug 20 is at the front of the sleeve 21 and the sleeve is so disposed as to position the said lug at the front of handle-bar 14. The said disposition of the lug allows complete clearance for the movement of the handle-bar, 13 relatively to the handle-bar 14 for exerting a force against the frame 10 at the top to jamb the frame gas-tight in the main. In addition, the provision of the lug 20 at the front of sleeve 21 and handle-bar 14 more effectively applies the force developed by turning the nut 17 forwardly on the hook 16 and it furthermore promotes convenience in the manipulation of the several elements.

In order to strengthen the structure I provide on the outer telescoping member 12^a a sleeve 25 and provide brace arms 26 pivotally connected to said sleeve 25 and to opposite sides of collapsible frame 10. The brace 28 is pivoted at one end to sleeve 25 and at its opposite end is pivoted to a sleeve 27 freely slideable on handle-bar 14. I may also, as shown, provide a bar 29 extending upwardly from sleeve 27 along bar 14 through a slot 31 in lug 20. Thus sleeve 27 may slide on bar 14 in the collapsing and distention of frame 10 and at all times the brace 28 will be in bracing relation to said bar 14 and said frame. The numeral 30 indicates a nut threaded on the bar 29 and adapted to bear against sleeve 23 to hold the brace members rigid.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

What I claim is:

1. A gas main stopper including an expandable frame, means on the frame to effect

- the stoppage of the main, handle bars on the sleeve adjustable along one of the handle frame, means to cause expansion of the frame by a longitudinal movement of one handle-bar, a sleeve adjustable along one handle bar and a bracing connection between said sleeve and said frame, said bracing connection being additional to said expansion means.
2. A gas main stopper including a frame, material on said frame to effect a closure of the main, telescoping members connected with the frame at points diametrically opposite, a sleeve on one of the telescoping members, arms pivotally secured to said sleeve and to the frame at diametrically opposite points, handled bars pivotally connected with the frame at substantially diametrically opposite points on the frame, a second sleeve adjustable along one of the handled bars and provided with means to engage a gas main at an opening therein, means to exert pressure on the other handled bar to lock the stopper in the main, means on said second sleeve engageable by the means to exert pressure on said other handled bar, a third sleeve slideable on the same bar as the second sleeve and members pivotally secured to said third sleeve and to said frame to constitute a brace.
3. A gas-main stopper, handle bars pivotally connected at substantially diametrically opposite points with the stopper, a sleeve adjustable along one of the handle bars and provided with means to engage a gas main at an opening therein, a second sleeve on the same bar with the first sleeve, and bracing means connecting said second sleeve with said stopper.
4. A gas main stopper including a frame, material on said frame to effect a closure of the main, telescoping members connected with the frame at points diametrically opposite, a sleeve on one of the telescoping members, arms pivotally connected to said sleeve and to the frame at diametrically opposite points, handled bars pivotally connected with the frame at substantially diametrically opposite points on the frame, a second sleeve adjustable along one of the handled bars and provided with means to engage a gas main at an opening therein, means to exert pressure on the other handled bar to lock the stopper in the main, means on said second sleeve engageable by the means to exert pressure on said other handled bar, a third sleeve slideable on the same bar as the second sleeve, members pivotally connected to said third sleeve and to said frame to constitute a brace, a rod extending upwardly from the third sleeve and a nut on said rod adapted to bear against said second sleeve.

PATRICK GOODMAN.
